IMPREGNATION OF TEXTILE MATERIALS
BY LATEXJean Etienne Charles Bongrand, Paris, and Léon
Sylvain Max Lejeune, Wasquehal, FranceApplication October 28, 1932, Serial No. 640,128
In France July 19, 1932

9 Claims. (Cl. 91—68)

This invention consists of improvements in or relating to the impregnation of textile materials by latex.

The expression "textile materials" is used to include fibres, rovings, slivers, yarns, threads, cords, felts, tissues and fabrics.

It is known that in order to impregnate textile materials with liquid rubber latex or any aqueous dispersion prepared from natural coagulated rubber, artificial rubber or regenerated rubber, immersion is employed and sometimes recourse is had to mechanical aids such as the application of vacuum and of pressure. Reference may be made to U. S. Patents Nos. 1,959,723, dated May 22, 1934, and 1,964,658, dated June 26, 1934.

Again it has already been proposed to facilitate the impregnation by pretreatment of the fibres or of the latex (including the addition of wetting or peptising agents or the like to the latex). Reference may be made to the specification of our concurrent application No. 640,126, filed Oct. 28, 1932.

This invention comprises a process for facilitating the impregnation of textile materials by latex in which after impregnation the textile materials are maintained in a humid atmosphere containing vapours of an anti-coagulating agent and the textile materials in the form of bobbins, rolls or the like are caused to turn or rotate slowly. Preferably, the atmosphere in which the textile materials are maintained is charged with moisture and with ammonia. The process which is in the nature of a maturing or ripening operation may be continued for hours and has the effect of increasing the penetration of the latex into the fibres and therefore increasing the quantity of rubber fixed in said fibres.

By the terms "ripening" or "maturing" operation, as used in this specification, is meant the process of maintaining a textile material impregnated with an aqueous rubber dispersion in an atmosphere in which evaporation of moisture can only take place slowly and in which coagulation of the rubber is prevented in order that complete impregnation of the fibres of the textile material may be effected, the impregnation being accompanied by an increase in the viscosity of the latex.

During the maturing period, the liquid latex continues to penetrate into the fibres and where fibres before maturing have been superficially impregnated, deep impregnation may be ensured; the latex is maintained in a liquid state and after a period which varies according to the nature of the textile material the latex succeeds in wetting

and penetrating each of the fibrils. On proceeding subsequently to coagulation, each of these fibrils will be penetrated and surrounded by coagulated rubber.

This process is preferably carried out in conjunction with the processes described in our aforesaid patents.

In order to carry out the maturing operation according to this invention two conditions must be observed:

(1) It is essential to avoid coagulation of the latex through drying or other cause.

(2) Draining of the latex away from textile material must be avoided.

The first condition is satisfied by allowing the impregnated materials to remain in a chamber the atmosphere of which is very moist and is charged with an anti-coagulant, such as ammoniacal vapours. The humidity of the atmosphere prevents the drying of the latex and the anti-coagulating agent prevents coagulation (owing for example to the carbon dioxide of the air) and has a definite retarding effect on the coagulation.

The second condition is satisfied by a turning movement of the bobbins or rolls of textile material. For example, the bobbins may be arranged with their axes horizontal on the vertical face of a disc slowly rotating on a horizontal axis. The effect of the slow turning of the bobbins of impregnated textile materials is to prevent the draining of the liquid latex away from the material. The maturing operation may be prolonged as long as is necessary to ensure the complete penetration of the fibres.

The accompanying drawing represents diagrammatically and by way of example the arrangement of a ripening installation according to the present invention.

In this drawing:

Figure 1 is a view in elevation of the installation.

Figure 2 is a view in plan thereof.

Figure 3 is an end view thereof.

As represented in the drawing, the installation comprises a pump 1 which draws water from a tank 2. This water is led through the conduit 3 and is evaporated by the humidifiers 4 situated in the upper part of the room 5. The excess of water returns to the tank through the pipe 6.

A hygrometer enables the degree of humidity to be watched and regulated.

The water of the tank 2 may be ammoniacal or may contain any suitable product which, when vaporized, will retard the coagulation of the rub-

ber. If the bath with which the textiles have been impregnated is rich in ammonia, pure water alone may be evaporated in the room.

5 Maturing wheels 7^a , 7^b , 7^c , 7^d , are disposed on one shaft 8 rotating at a low speed, for example, about four revolutions per minute.

The bobbins 9 of impregnated textile materials are disposed on spindles 10 fixed to the two faces of each wheel.

10 The ripening room is kept closed and at a temperature of 15 to 20° C. The impregnation latex cannot coagulate in this atmosphere.

15 The movement of the wheels 7^a , 7^b , 7^c , 7^d , causes the drops of liquid, which would have a tendency to run off the bobbins under the influence of gravity, to be reabsorbed by the textile and the impregnation which has thus been initiated may be extended for several days if necessary.

20 Microscopic and ultra-microscopic examination of the textile fibres have proved that, after such ripening, the impregnation by liquid rubber latex was much deeper than without this ripening.

We claim:

1. A process for facilitating the complete impregnation of textile material with rubber which comprises treating the said textile material wound in the form of bobbins with rubber latex and subsequently maintaining the textile material while still wet with the rubber latex in a humid atmosphere containing vapors of an anti-coagulating agent, the excess of latex being retained in contact with the said textile material by the slow rotation of said bobbins.

35 2. A process for facilitating the complete impregnation of textile material with rubber which comprises treating the said textile material wound in the form of bobbins with rubber latex and subsequently maintaining the textile material while still wet with the rubber latex in an atmosphere charged with moisture and with ammonia, excess of latex being retained in contact with the textile material by slow rotation of said bobbins.

40 3. A process for the maturing of latex-impregnated textile materials which consists in moving the said impregnated textile material while still wet with the impregnating liquid slowly in a humid atmosphere containing vapors of a volatile

anti-coagulating agent, thereby preventing liquid from dropping from the textile material.

4. A process for the maturing of latex-impregnated textile materials which consists in moving the said impregnated material while still wet with the impregnating liquid slowly in a humid atmosphere containing ammonia, thereby preventing liquid from draining from the textile material.

5 5. A process for the maturing of latex-impregnated textile materials which consists in moving the impregnated material while wound in the form of bobbins and while still wet with the impregnating liquid slowly in a humid atmosphere containing ammonia vapor, thereby preventing liquid from draining from the textile material.

10 6. A process for the maturing of latex-impregnated textile materials while wound in the form of bobbins which consists in moving the bobbins while still wet with the impregnating liquid slowly in an atmosphere charged with moisture and with ammonia vapor, thereby retaining the excess of rubber latex in contact with said textile material.

15 7. A process for the maturing of latex-impregnated textile materials wound on bobbins which consists in moving the bobbins while still wet with the impregnating liquid in a humid atmosphere containing ammonia, excess of latex being retained in contact with the textile material by slow rotation of said bobbins.

20 8. A process for the maturing of latex-impregnated textile materials wound on bobbins which consists in rotating the bobbins while still wet with the impregnating liquid slowly upon their axes in a closed chamber containing a humid atmosphere and charged with ammonia vapor so as to prevent liquid from draining from the textile material.

25 9. A process for the maturing of latex-impregnated textile materials wound on bobbins which consists in turning the bobbins while still wet with the impregnating liquid in a closed vessel maintained at a temperature between 15° and 20° C. and containing a humid atmosphere and ammonia vapor so as to prevent latex from draining from the bobbins.
